UNITED STATES PATENT OFFICE.

WILLIAM W. STEWART, OF MUSCATINE, IOWA.

IRONING-BOARD.

1,132,498.

Specification of Letters Patent. Patented Mar. 16, 1915.

Application filed February 20, 1914. Serial No. 820,011.

To all whom it may concern:

Be it known that I, WILLIAM W. STEWART, a citizen of the United States, residing at Muscatine, in the county of Muscatine and State of Iowa, have invented new and useful Improvements in Ironing-Boards, of which the following is a specification.

This invention relates to ironing boards and more particularly to means for supporting one end thereof.

The principal object of the invention is the provision of simple and efficient means for connecting the ironing board to a wall or other similar upright support in a convenient and expeditious manner.

Further objects of the invention will appear as the following description is read in connection with the accompanying drawing, which forms a part of this application, and in which:—

Figure 1 is a perspective view of the wall bracket. Fig. 2 is a perspective view showing the board attached to said bracket.

In the specific embodiment of the invention as illustrated herein, the board 1 is provided with the usual supporting leg 2 and the end of the board which is fastened to the wall or other support is slightly rounded, as shown at 12. Secured to one side edge 30 of the board and projecting beyond the same and having an inwardly turned end 13 is a strap 14 the inwardly turned end 13 of which is arranged to engage an aperture in the offset 15 of the wall bracket 16. This wall bracket is constructed of resilient metal, being substantially U-shaped in outline and provided with apertures in each offset 15, as shown. Pivoted to the opposite side edge of the board is a similar strap to 40 that indicated at 14 which is adapted to engage the aperture in the opposite offset to that which is engaged by the inwardly turned end 13, this strap also having an inwardly turned end 17 for that purpose.

In applying the board to the wall bracket 45 the board is angled away from the operator and the inwardly turned end 13 inserted in the aperture in the offset. The board is then brought around at right angles to the wall or other support and the inwardly 50 turned end 17 engaged with the aperture in the opposite offset. It will be noticed that in doing this the curved portion of the board places that portion of the bracket 16 between the offsets under tension so that the 55 hooked or inwardly turned ends 13 and 17 are held firmly in the apertures. A retaining device 18 is pivoted to the board and arranged to hold the strap 17 against displacement when once applied. 60

By providing a connection or support of this character the owner may be supplied with three or four wall brackets so that the board may be set up in that part of the house most available and most convenient at 65 the time. It will also be noticed that by utilizing a single supporting leg the board may be folded into extremely compact form for storage. 70

What is claimed is:—

In combination, a board having a single supporting leg hinged thereto, a substantially U-shaped resilient wall bracket, said board having a curved end, a permanent hook connected to one side of the board and 75 arranged to engage one of the apertures in the bracket and a hinged hook carried by the opposite side of the board arranged to engage the other aperture, said board being adapted to flex the bracket when in position 80 so that strain is placed upon the hooks to prevent their disengagement.

In testimony whereof I affix my signature in presence of two witnesses.

WILLIAM W. STEWART.
